UNITED STATES PATENT OFFICE.

JAMES E. DOOLITTLE, OF BRIDGEPORT, CONNECTICUT, ASSIGNOR OF ONE-HALF TO GEORGE E. HAWES, OF SAME PLACE.

NAVAL GAME-BOARD.

SPECIFICATION forming part of Letters Patent No. 625,248, dated May 16, 1899.

Application filed August 17, 1898. Serial No. 688,767. (No model.)

To all whom it may concern:

Be it known that I, JAMES E. DOOLITTLE, a citizen of the United States, and a resident of Bridgeport, in the county of Fairfield and 5 State of Connecticut, have invented certain new and useful Improvements in Naval Game-Boards, of which the following is a specification.

My invention relates to an improved game-board; and it consists in certain details of 10 construction to be more fully set forth in the following specification.

To enable others to understand my invention, reference is had to the accompanying 15 drawings, in which—

Figure 1 represents a plan view of my improved game-board with the movable figures properly arranged to play the game. Fig. 2 is a detail side elevation of one of the movable 20 figures and broken sectional view of the board. Fig. 3 is a detail side elevation of one of the immovable figures and broken sectional view of the board. Fig. 4 is a modified construction of the game-board.

25 Its construction and operation are as follows:

The surface of the board A is laid off in alternate white and black squares like an ordinary checker or chess board and represents a 30 bay or other large body of water. B and C represent harbors connected to the former by means of the narrow channels D E.

The movable characters *a b c d e f g h i j k m n o p q r s t* represent gunboats or other 35 naval vessels, while the squares on which they move are numbered from 1 to 36, inclusive.

Within the harbors B and C are the forts F G H I J K M N, having the holes *a'* therein to receive flagstaffs, one of which staffs *b'*, 40 carrying the flag *c'*, is shown at Fig. 3, it being understood that in playing the game, or rather at its commencement, each one of the forts F, G, H, I, J, K, M, and N will have a flag mounted therein.

45 Each of the vessels will be furnished with a turret *d'* for convenience in handling and each turret will have the hole *e'* to receive one of the flags from the forts which one player strives to capture from the other.

50 O P Q R represent four mines near the entrance of each of the harbors B and C, whose

object will be more fully explained herein-after.

The boats, which represent men on an ordinary checker-board, are first placed as shown 55 at Fig. 1. The objective point of the player is to pass through the narrow channels D and E into the harbors B and C and if successful in reaching a square in said harbors is entitled to take the flag from the fort adjacent to 60 said square and transfer the same to his vessel, (see Fig. 2,) which vessel is then designated as a "flag-ship," and it is then at liberty to move in any direction, like a crowned man in a square of checkers, while the vessels 65 that are not flag-ships can move only in one direction. When a vessel is forced to occupy either of the squares 7, 10, 27, or 30 opposite the mines O P Q R, they are virtually destroyed, owing to the fact that being able to move (unless a flagship) only in one direction they are 70 thus put out of the game.

If desired, the two additional harbors B' and C' can be located on the remaining sides of the boards A, as shown at Fig. 4. 75

It will be understood that while I show a turret projecting from the upper surface or deck of the vessel to provide handy means to manipulate said vessel and also to receive a flag this can be dispensed with and a hole 80 provided for the flagstaff in the vessel itself. Also other shaped characters can be used, if desired, in playing the game.

Having thus described my invention, what I claim as new, and desire to secure by Letters 85 Patent, is—

1. In a naval game-board of the character described, the combination with a large checkered field representing an open bay of two or more smaller checkered fields representing 90 harbors oppositely placed with respect to such large fields and separated therefrom by a narrow channel sufficient for the passage of only one at a time of the characters used in playing the game, and which smaller checkered 95 fields are out of line with each other, and placed entirely outside of the main checkered field, forts or other like stationary receptacles in said harbors for holding flags or other removable trophies of like character, for the 100 purpose set forth.

2. In a game-board of the character de-

scribed, the combination, with a large checkered field representing an open bay, of two or more smaller checkered fields out of line with each other, and placed entirely outside of the 5 main checkered field representing harbors oppositely placed with respect to the said large fields and separated therefrom by a single square representing a narrow channel sufficient for the passage of only one at a time of 10 the boats, or other like characters used in playing the game, forts or other like stationary points in said harbors for holding flags or other removable trophies, means on said mov-

able characters or boats for receiving said trophies, mines substantially as shown, located on the borders of the main field or bay, all substantially as described and for the purpose set forth. 15

Signed at Bridgeport, in the county of Fairfield and State of Connecticut, this 11th day 20 of August, A. D. 1898.

JAMES E. DOOLITTLE.
